UNITED STATES PATENT OFFICE.

BERNE NADALL, OF KINGSTON-UPON-THAMES, ENGLAND, ASSIGNOR TO
THE LINOTYPE COMPANY, LIMITED, OF LONDON, ENGLAND.

DESIGN FOR A FONT OF TYPE ORNAMENTS.

SPECIFICATION forming part of Design No. 35,810, dated March 11, 1902.

Application filed January 25, 1902. Serial No. 91,291. Term of patent 14 years.

To all whom it may concern:

Be it known that I, BERNE NADALL, a citizen of the United States, residing at Kingston-upon-Thames, in the county of Surrey, 5 England, have invented and produced a new and original Design for a Font of Type Ornaments, of which the following is a specification.

My design is clearly shown in the accompanying typographical impressions, the types composing the font being numbered 1 and 2.

The main feature of the design presented by each of the types composing the font is that within a substantially equal-sided rectangular space are arranged two entwined scrolls, each terminating at its inner end in a conventional leaf-like form representing somewhat a caladium leaf, which leaf-like forms are connected. The scrolls are formed 10 by single solid lines and are provided at suitable points with outwardly-extending projections and with inwardly-extending branch lines which extend to the leaf form of the opposite scroll. The general effect of the design 15 is that of two connected leaves surrounded by a border or frame formed by the stems on which said leaves are supported.

In the form numbered 1 the free outer end 20 of the scroll forming the left-hand side of the design terminates at the upper right-hand

corner of the square within which the design can be considered as being inclosed and the free end of the scroll forming the right-hand side of the design terminates at the lower left-hand corner of said square. In the form numbered 35 2, however, the relative positions of these parts are reversed—that is, in this form the scroll which extends to the right-hand side of the design has its outer free end extending to the upper left-hand corner and the scroll 40 forming the left-hand side of the design has its free end extending to the lower right-hand corner.

The several type ornaments herein described are of uniform design and are adapted to be grouped in various ways to form borders and other composite typographic ornaments.

Having thus described my invention, what I claim as new, and desire to secure by Letters 45 50 Patent, is—

The design for a font of type ornaments, substantially as herein shown and described.

In testimony whereof I affix my signature in presence of two witnesses.

BERNE NADALL.
